UNITED STATES PATENT OFFICE.

WILLIAM GUY RUGGLES, OF SAN FRANCISCO, CALIFORNIA.

OBSERVATION-STATION.

1,352,992.

Specification of Letters Patent. Patented Sept. 14, 1920.

Application filed September 14, 1916. Serial No. 120,173.

To all whom it may concern:

Be it known that I, WILLIAM GUY RUGGLES, a citizen of the United States, and resident of San Francisco, in the county of

5 San Francisco and State of California, have invented certain new and useful Improvements in Observation-Stations, of which the following is a specification.

My invention relates in general to an observation station or buoy and particularly relates to such a device designed to constitute a control and observation station for a submarine or other anchoring or receiving station positioned beneath the water.

15 At present submarines have the disadvantage in that when at the surface they are subjected to attack either by gun fire or by ramming because the period of time required in order to submerge is sufficient to permit 20 the enemy to destroy the boat before it can sink out of the danger zone. The submarine must sink until its periscope or any other evidence of its presence is below the surface, but when so submerged the crew of the 25 submarine have no means of acquiring information as to what may be on the surface. At present it is necessary for the submarine to come up in order to make an observation.

As a submarine can be seen from an aero- 30 plane when the boat is thirty or forty feet below the surface and the submarine cannot see until its periscope is above the surface, obviously the submarine is at a disadvantage.

35 Accordingly one of the primary objects of the invention is to provide a simple form of mechanism by means of which a submarine submerged below the danger zone and even resting on the bottom of the water 40 may make observations on the surface with the least possible risk of detection.

I attain this object broadly by providing a water tight tank of a size sufficient to contain an observer and, if desired, equipped 45 with a small periscope and with means for communicating observations back to the submarine or other receiving station. Such a device can be passed out of the submarine or other container and floated to any position slightly below the surface desired by 50 the observer and from this position observation can be made with comparative safety.

Incidental to this general object it is a further desideratum to provide a construction in which the observer may be quickly introduced and in which the observer-con-

taining tank or vessel may be passed from the submarine free of any possibility of introducing water accidentally either into the submarine interior or into the interior of 60 the observation tank.

Another object of the invention is to provide a simple and easily controlled mechanism for regulating the movements of the observation tank and still another object 65 is to provide a simple form of communicating means between the observer and the navigating or other officer of the submarine.

Still another object is to provide a type of observation tank which can be opened 70 as desired to the outside air for the purpose of supplying air to the observer and thus conserve the supply of artificial air carried by the tank.

Various other objects and advantages of 75 the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

Referring to the accompanying drawings: 85

Figure 1 is a view of a body of water showing a submarine in outline, submerged below enemy battleships on the surface and enemy aeronautical devices above the surface and showing a preferred embodiment 90 of my invention in connection with the submerged submarine;

Fig. 2 is a view in side elevation of a transferring tank constituting part of the submarine and with its parts in closed position;

Fig. 3 is a view similar to Fig. 2, taken at right angles thereto and showing both the transferring and observation tanks with their parts in open position to receive the 100 observer;

Fig. 4 is a view partly in side elevation and partly broken away to show some of the internal construction and contents of the observation tank;

Fig. 5 is a detail of the joint between the two parts of either the observation or the transferring tank;

Fig. 6 is a vertical sectional view through an enlarged view of the closing cap at the 110 bottom of the observation tank;

Fig. 7 is a transverse sectional view taken

through the cable connection of Fig. 6; and taken on the line 7—7 of Fig. 6;

Figs. 8, 9, 10 and 11 are transverse sectional views taken respectively on the lines 5 8—8, 9—9, 10—10, and 11—11 of Fig. 4.

In the drawings and referring particularly to Fig. 1 there is shown a receiving station 12, which for the purpose of this disclosure may be considered as a submarine 10 herein shown to be submerged and positioned a distance below the surface, indicated by the line 13 sufficient to remove the submarine out of any danger of ramming, of gun-fire from the war-ships 14 on the surface, and below the depth at which it might 15 be seen from the aeroplane 15. There is also shown in Fig. 1 an observation tank 16 of relatively small size but of sufficient capacity to contain an observer positioned 20 therein. This tank is shown in its normal observing position and provided with a periscope 17 with its eye 18 positioned slightly above the level of the water and with the observer-containing-portion of the tank submerged 25 below the surface. The tank is shown floating above the submarine and connected thereto by means of a flexible cable 19.

This flexible connection may also provide 30 a means of communication between the observation and the receiving stations and for this purpose may include an insulated telephone wire 20 (see Fig. 4) connected with a telephone head-piece 21 worn by the operator in the observation tank. The other end of the telephone wire makes proper connection with a coacting telephone apparatus in the submarine.

The twist of the flexible connection 19 is 40 very apt to cause a rotary movement of the observation tank and in order to minimize this rotary movement about the vertical axis, the upper end of the tank is provided with a guiding fin construction 22 in the form of 45 a flat plate extending longitudinally of the tank and on opposite sides of the periscope tube 23 and attached to the lower ring 45 to form a buttress brace for this tube.

The observation tank and its contents are 50 non-magnetic so as to permit the use of a magnetic compass, if desired and is preferably of cylindrical form with a frusto-conical lower end 24 and a dome-shaped upper end 25 constituting closing means at 55 opposite ends of the tank and designed to withstand the severe external water pressures without distorting the construction. The tank is preferably formed of two parts or sections with the adjacent open ends 60 telescoping with an interrupted bayonet form of screw joint usually used in forming water-tight joints. The quick acting joint includes loosely fitting threads 27 (see Fig. 5) and suitable ring packing members 65 28 disposed between the end threads of one

part and the adjacent side of the other part. The threads are of materially less cross-section longitudinally of the tank than their containing grooves 29 whereby slight longitudinal play is permitted between the parts 70 or sections and the packing is so arranged that a collapsing movement between the sections affected by end pressures on the tank causes the packing to become compressed and thus further insure a water-tight condition at the joint. The upper end 25 is provided with eye ports 25', through which the observer can see out through the top of the observation tank. 75

The apex of the lower end 24 is formed of 80 a bushing plug 31 (see Fig. 6) having a reduced threaded portion 32 screwed into the end 24 and recessed from its inner end to a compartment 33. The flexible connection 19 containing the electric cable or 85 wire 20 is passed through the plug and the wrappings 34 of the cable are separated and flared outwardly. The flared portion of the wrappings is fastened between a ring 35 and a plate 36 which coact to form a carriage 90 rotatably mounted upon roller bearings 37 within the compartment. The conducting wire 20 of the cable is passed through a tube 37' rigidly attached to the plate 36 and passing up through a gland 38 95 threaded into the inner end of the portion 32 thus closing the compartment. The gland includes a stuffing box 39 designed to provide a water-tight joint between the conducting wires and the bushing plug to prevent leakage into the interior of the tank at 100 this point.

The periscope tube 23 is formed of a plurality of sections suitably connected, the upper section of which is tapered so as to provide the necessary space at the lower portion for the optical elements of the periscope and at the same time provide the least possible size of target for the enemy gunners, and is rotatably mounted in the dome-shaped head 25 preferably to one side of the axis of the tank so as to position the periscope eye piece 40 as close to one side of the tank as possible and thus give the operator the maximum available moving space 115 within the small quarters provided by the tank. The tube is rotated by some suitable crank mechanism 41 and is arranged to direct the eye 18 of the periscope in any direction about its vertical axis. Two fluid conducting tubes are fixed to the outside of the periscope tube, one of which tubes 43 has its upper end positioned relatively close to the eye 18 in a position to direct a cleansing substance across the eye to clean the same 125 and the other tube 44 has its upper end positioned slightly below the upper end of the tube 43. The fluid tubes are carried by the periscope tube and are supported on a plurality of rings 45 spaced longitudinally 130

of the periscope tube and fixed in position so that the periscope tube is free to rotate. The fluid tubes are positioned close to the outer surface of the periscope tube as shown in the sectional views in Figs. 8-10 and are positioned approximately 90° to each other so that the apparent diameter of the periscope tube is increased by not more than the diameter of one of the fluid tubes when viewed from any horizontal angle, and are led into the float through the head 25 and adapted to be closed by stop cocks provided with nipples to receive the flexible air tubes hereinafter described.

15 A cleaning outfit may be provided, which in this instance includes a tank 46 of alcohol and a tank 47 of compressed air adapted to be connected by a flexible tubing 48 with the inner end of the tube 43 to project a 20 mixture of alcohol and air forcibly across the eye of the periscope to clean the same of oil or other foreign substances which might interfere with the clear vision through the periscope. These two tubes 25 can also be used in connection with a breathing bag to draw air into the tank through the tube 43 and to expire through the tube 44.

In this way the supply of artificial air 30 may be conserved while the observer is at the surface of the water. The observation tank is also provided with a pressure gage 49 or other mechanism for indicating the depth at which the observation tank is 35 floating.

In order to transfer the observer from the interior of a submarine or other inclosed space to and from the observation tank, there is provided a transferring receptacle, 40 shown more particularly in Figs. 2 and 3. This receptacle includes a two-part cylindrical casing, designed to project above the deck of the submarine and attached thereto by some suitable means, such as the flange 45 plate 50, encircling the upper portion 51 of the receptacle. This plate is preferably adjustable on the tank so as to fit within a suitably constructed man-hole in the top deck of the submarine and to space the lower 50 end of the upper section a distance from the floor 52 of the submarine merely sufficient to swing the lower section into its engagement with the upper section with the minimum amount of lifting operation. The upper portion of the receptacle is designed to 55 contain the relatively short upper portion of the observation tank together with the periscope tube and the lower portion 52 is similarly designed to contain the lower portion 60 of the observation tank when the parts of the tank are separated from each other as shown in Fig. 3. When the parts of the transfer tanks are separated, the upper portion of the observation tank is maintained in 65 position by means of some suitable keeper

53. The parts of the transfer tank are fastened together by means of interrupted thread connections similar to those described for the parts of the observation tank, which connection may be reinforced by an externally disposed strap band 55, the ends of which are arranged to be drawn together by a turn-buckle 56. A pair of differential hoist mechanisms 57 positioned on opposite sides of the tank may be used to handle the 70 lower section of the transfer tank. The upper end of the transfer tank is positioned above the deck of the submarine, and is designed to be opened to permit the passage of the observation tank to and from the interior of the transfer tank. The upper end of this tank is closed by means of a cover 58 provided with a pivoting extension 59 projecting to one side thereof and positioned between a pair of brackets 60 projecting 85 from the side of the tank. The cover is manipulated from within the submarine by means of an actuating rod 61 having a worm and segmental gear connection 62 with the extension of the cover. The cover is securely 90 fastened to the tank by means of bolts 63 passed through the plate 50, operated from the interior of the submarine and having threaded ends 64 engaging in threaded sockets 65 in extension 66 projecting from 95 the periphery of the cover.

The portion of the flexible connection opposite the end attached to the observation tank is passed about a winding drum 66' rotatably mounted within the lower portion 100 52 of the transferring tank and actuated exteriorly of the tank through a worm and gear drive 67 in turn actuated from a suitably disposed electric motor 68. As previously suggested the flexible connection 105 contains the telephone or other electric wires communicating with the observation tank and the inner end of these electric wires are passed through an opening 69, in the hub shaft 70 of the drum and through a water-tight plug 71 into the interior of the submarine so as to make proper connection with the receiving station and other mechanism controlled from the observation tank. A water pipe 72 designed to be connected with 110 the water ballast tanks of the submarine opens through a port 73 in the lower end of the transfer tank. In order to permit the escape of air from the space between the transfer tank and the observation tank an 115 air pipe 74 opens from the top of the space within the transfer tank into the submarine and the air is permitted to escape through a cock 75 accessible from the interior of the submarine. An equalizing pipe 76 is in 120 fluid communication with the pipe 72 and leads either to the outside of the submarine or to any apparatus containing a pressure equal to the water pressure about the submarine. A device of this character is suffi- 125 130

- 1 ciently self contained that it may be secretly manufactured, stored at convenient points, and in time of war installed in submarines prepared to receive it simply by bolting 5 flange 50 (Fig. 3) to a man-hole in the deck designed for this purpose.
- In operation and with the tank parts in their open position shown in Fig. 3, the observer takes his position within the lower 10 part of the observation tank with some suitable breath purifying apparatus and the two parts of the tank are raised into telescoping position by means of the differential hoists and the parts are securely fastened together 15 by any approved means, as by means of a large wrench rotating the threaded parts into interlocking position. Likewise the parts of the transfer tank are similarly fastened together, so that there is a water-tight 20 connection between the parts of the observation tank and between the parts of the transfer tank. The water pipe is then open to the water ballast tank in the submarine so as to admit water to the space between the 25 tanks and at the same time air is permitted to escape from the transfer tank through the cock 75. Finally the pipe 76 is opened so as to equalize pressure and permit an inspection of the joints before the cover is 30 opened. The cover controlling the opening into the transfer tank from the outside of the submarine is then loosened by rotating the bolts holding the cover in place and when free of the holding means the cover 35 is swung into open position. The buoyancy of the observation tank will cause it to rise out of the transfer tank and move upwardly toward the surface of the water, the ascent being permitted and controlled by any suitable 40 mechanism regulating the rate at which the take-up drum is allowed to rotate. The observer in the tank can ascertain, by means of his pressure gage, the approach to the surface and eventually can judge by the 45 amount of light seen through the ports just how close he is to the surface and can indicate to the receiving station to apply a brake to the drum or otherwise control the position of the tank.
- 50 The observer connects the flexible tubing attached to alcohol and compressed air tanks 46 and 47 to the nipple of the stop cock closing the inner end of fluid pipe 43, and upon reaching the surface, should floating oil or 55 other matter dim or obscure the eye of the periscope he may turn same until the outer lens faces the outer orifice of the pipe 43 and by gentle blasts of alcohol and air clean and dry same quickly.
- 60 The observation tank may be equipped with a type of periscope in which the field bounded by the horizon is vertically disposed and associated with a compass card arranged so that the observer can report 65 by 'phone or otherwise to the submarine of-

ficers that any enemy boat or aeroplane of a particular character is at such a distance and in a particular direction from the position of the observation tank.

Should the observation continue longer 70 than a few seconds the observer may, by the same means, blow the water out of pipe 44, and attaching a flexible tube exhale through same, inhaling through pipe 43 using a breathing bag to arrest any moisture that may enter pipe 43. Observations covering considerable periods of time are thus made possible in a locality patrolled by air-crafts in advance of the movement of ships, and the submarine by lying quietly 80 gives no warning to enemy microphones of her presence.

The observer returns to the submarine by reversing the operation by which he left it.

This device renders unnecessary the fatal 85 danger of a submarine being shelled or rammed by rising close to a boat lying quietly on the surface, and upon which the submarine's microphones are not operative.

In the last analysis this invention enables 90 a submarine boat to enter the sea under the midst of an enemy fleet, and from a position of minimum danger to itself intelligently direct the maximum of destruction upon the most important ships of that 95 enemy.

In this specification reference has been made to a submarine as the receiving and control station for the observation tank, but it is obvious that the device may be operated from a stationary submerged compartment and when considered in this connection it will be noted that the device may constitute a feature of coast and harbor defence. Such an observation station situated 100 off the coast may be utilized as a fire control station for shore batteries and can indicate positions of approaching hostile boats including submarines with the least possible risk of detection.

Having thus described my invention, I claim:

1. In a device of the class described, the combination of an anchorage, a floating body of cylindrical form adapted to float 115 in an upright position, a flexible connection between the floating body and anchorage, said body provided with a fin construction rigidly connected thereto and extending in a plane containing the axis of the cylindrical body for minimizing rotary movement of the floating body.

2. In a device of the class described, a floating body provided with a periscope and provided with a fin construction held in fixed position relative to the periscope and thus tending to hold the field of view through the periscope.

3. In a device of the class described, an observation tank provided with a periscope 130

and designed to accommodate an observer, a connection with the tank and means for resisting any tendency of the tank to rotate the periscope.

5 4. A cylindrical observation tank adapted to float upright in the water, means engaging the bottom end of said tank for controlling the same and a fin construction at the upper end of the tank rigidly fixed thereto and extending parallel to the length of the tank.

10 5. An observation tank having a periscope tube extending upwardly therefrom and a fin construction for resisting rotary movement of the tank, said fin construction constituting a brace for the periscope tube.

15 6. An observation tank provided with externally actuated means for controlling the submerged position thereof, and a thin guiding fin fixed to the upper portion of the tank for retarding rotary movement thereof about a vertical axis.

20 7. A metallic cylindrical observation tank having a rigidity sufficient to withstand water pressure at great depths and having a capacity to accommodate an observer and including two shells having closed ends and having a water tight interfitting joint therebetween, said joint including a loosely fitting threaded connection, the end of one of said shells being provided with an observation port, and means within the closed tank for communicating exteriorly of the tank.

25 8. In a device of the class described, a cylindrical observation tank including two interfitting sections, a bayonet screw-threaded connection between said sections, the threads of said connection being materially less in cross-section than their containing grooves whereby slight longitudinal play is permitted between the sections and a packing compressed by a collapsing movement between the sections.

30 9. In an observation tank, a bearing extending through a side of the tank, an electric cable passed through the bearing, said bearing provided with a compartment, a carriage rotatably mounted in said compartment with the outside wrapping of cable affixed thereto, the conducting wires of the cable extending through the bearing into the interior of the tank.

35 10. In an observation tank, a bearing extending through a side of the tank, an electric cable passed through the bearing, said bearing provided with a compartment and a bushing, a carriage rotatably mounted in said compartment with the outside wrapping of cable affixed thereto, the conducting wires of the cable extending through the bushing into the interior of the tank.

40 11. In a device of the class described, the combination of an observation tank, a continuous electric cable leading through a side

of the tank and provided with wrappings leading to the tank and rotatable means for fastening the wrappings of the cable to the tank, and anti-friction bearings disposed between said rotatable means and said tank. 70

12. In a device of the class described, the combination of an observation tank, an electric cable leading continuously through a side of the tank and into the interior thereof, rotatable means for fastening the wrappings of the cable to the tank and a water-tight joint between the cable and tank to prevent leakage into the tank. 75

13. In a device of the class described, a periscope tube, a pair of relatively small tubes carried by said periscope tube, the upper end of one of said tubes being disposed above the upper end of the other tube, one of said tubes designed to constitute an air inhaling tube and the other tube 85 designed to constitute an air exhaling tube.

14. In a device of the class described, a periscope tube, a pair of relatively small tubes carried by said periscope tube, the upper end of one of said tubes being disposed 90 above the upper end of the other tube, one of said tubes designed to constitute an air inhaling tube and the other tube designed to constitute an exhaling tube, said tubes disposed at approximately 90° to each other 95 circumferentially of the periscope tube whereby the apparent diameter of the periscope tube is increased not more than the diameter of one of the small tubes when viewed from any angle. 100

15. In a device of the class described, a periscope tube, a pair of relatively small tubes carried by said periscope tube, the upper end of one of said tubes being disposed above the upper end of the other tube, one of said tubes designed to constitute an air inhaling tube and the other tube 105 designed to constitute an air exhaling tube.

16. In a device of the class described, the combination of an observation tank, a periscope tube projecting upwardly from said tank, a plurality of rings spaced apart longitudinally on said tube, a tube paralleling the periscope tube and fastened to and supported by said rings, one end of said tube 115 terminating adjacent the periscope lens and the other end of said tube opening into the interior of the tank.

17. In a device of the class described, an observation tank provided with a periscope 120 having a relatively small cross section, means for rotating the periscope tube, a fluid conducting tube positioned close to the outside of the periscope tube and opening into the interior of the tank, and means for 125 fastening the fluid conducting tube to the periscope tube thereby to permit the periscope tube to rotate freely.

18. In a device of the class described, a transferring receptacle having an opening 130

- at one end thereof, a tank designed to be moved into and from the receptacle through said opening, means for closing the opening, said tank and receptacle being formed of separable parts with the joint of one positioned adjacent the joint of the other whereby they may be separated to provide access to the interior of the tank while said opening is closed.
- 10 19. In a device of the class described, a transferring receptacle formed of a two-part cylindrical casing adapted to be sepa-

rated to provide access to the interior thereof and provided with an outlet therefrom at one end, a closure for said outlet, and a 15 tank within said receptacle and removable therefrom through said outlet, said tank provided with means for giving access to the interior thereof when the parts of said receptacle are separated from each other. 20

Signed at New York city in the county of New York and State of New York this 12th day of September, A. D. 1916.

WILLIAM GUY RUGGLES.
